UNITED STATES PATENT OFFICE.

ELEANOR MARIE NEWLANDS, OF FRESHWATER BAY, ISLE OF WIGHT, ENGLAND.

DEVICE FOR SECURING HATS TO THE HEAD.

Application filed April 8, 1922. Serial No. 550,780.

To all whom it may concern:

Be it known that I, ELEANOR MARIE NEWLANDS, a British subject, and resident of Freshwater Bay, in the Isle of Wight, England, have invented certain new and useful Improvements in Devices for Securing Hats to the Head, of which the following is a specification.

This invention relates to devices for securing hats to the head. It consists of a length of elastic encased in tubular silk which is secured to the inside of the hat so as to form three sides of a square, the open side being at the front.

15 This encased elastic band runs freely through two loops of silk or the like which are attached at the back of the hat by suitable pins, and come the required distance apart, for instance four or five inches. The 20 two ends of the band are also provided with pins for attachment to the hat; these pins allow the band to be adjusted to the head.

And in order that the invention may be better understood it will now be described 25 with reference to the accompanying drawings in which:—

Figure 1 shows a side elevation of one end pin attached to the end of the elastic band.

Figure 2 shows front elevation of same. 30 Figure 3 shows end pin with its carrying clip ready for attachment to the end of the elastic band.

Figure 4 shows a side elevation of a double pin or fastener for attaching a loop 35 to the hat.

Figure 5 shows a front elevation of Figure 4.

Figure 6 shows a plan of Figure 4.

40 Figure 7 shows a sectional side elevation showing the method of attachment of a loop to the hat.

Fig. 8 shows the hat securer ready for attachment to a hat.

45 Figure 9 shows the hat securer attached in position inside a hat.

In the drawings *a* are end pins, carried by clips *b* which are adapted to be secured to the ends of the elastic *c*, which is encased in the tube of silk *f*. *d* are loops of tubular

silk and *e* are double pins or fasteners for 50 securing the loops in any desired positions as shown in Figure 7, where *h* shows a portion of the hat in section to which the double pin *e* is attached by passing the points through the material and turning 55 them down as indicated on the drawing.

In securing the device to the hat, the two loops *d* are attached towards the back of the hat on the interior, at a suitable distance apart and the band made from the parts *c* 60 and *f* with the end pins *a* is passed through the loops.

The end pins are adjustably fastened to the hat at the sides, according to the size of the wearer's head, leaving the front free as 65 shown.

The pins may either be bent back to form hooks or the end pins turned back on the band to give a hook effect.

It will thus be seen that the device is independent of any elastic or fabric across the forehead, or of any auxiliary elastic for passing beneath the hair, or of the use of slides or buckles or of any wire frame, or of pins worn in the hair, as in other known contrivances of the sort. 70

What I claim and desire to secure by Letters Patent in U. S. A. is:—

1. A device for securing hats to the head comprising an elastic strip encased in tubular silk, two loops fastened in position towards the back of the hat through which the said elastic strip encased in tubular silk is passed and means for adjustably fastening the two ends of the elastic strip to the hat 80 for the purposes set forth.

2. A device for securing hats to the head comprising an elastic strip encased in tubular silk, two loops fastened in position by double pins towards the back of the hat, 90 through which the elastic strip encased in tubular silk is passed and pins at the ends of the elastic strip for adjustably fastening the two ends of the elastic strip to the hat for the purposes set forth. 95

Signed at London in the county of London, this 31st day of March, A. D. 1922.

ELEANOR MARIE NEWLANDS.
